UNITED STATES PATENT OFFICE.

PAUL E. CARTER, OF BRONXVILLE, NEW YORK, AND ROY CONNELL, OF WESTFIELD, NEW JERSEY, ASSIGNORS TO GENERAL RAILWAY SIGNAL COMPANY, OF ROCHESTER, NEW YORK.

ELECTRIC INTERLOCKING SYSTEM.

Application filed August 16, 1923. Serial No. 657,715.

To all whom it may concern:

Be it known that we, PAUL E. CARTER and ROY CONNELL, citizens of the United States of America, residing, respectively, at Bronxville, county of Westchester, State of New York, and at Westfield, in the county of Union and State of New Jersey, have invented certain new and useful Improvements in Electric Interlocking Systems, of which the following is a specification.

This invention relates to power operated interlocking systems for railroads, and more particularly to the automatic control of switch operating mechanisms directly by an associated track circuit.

For reasons well recognized by those skilled in the art, it is essential in the interests of safety to organize a power operated interlocking system in such a way that the operator can not accidentally or carelessly throw a switch under a train or directly in front of it. The present invention deals more particularly with this problem, especially from the standpoint of obtaining the desired automatic control through the agency of a detector track circuit, rather than by the use of detector bars or the like. It may be explained that while this problem is of course common to all types of power interlocking systems, the particular embodiment of the invention herein disclosed is more especially applicable to electric interlocking systems, the various features of this particular embodiment, however, being adaptable in an obvious manner to systems of other types.

Generally stated, the principal objects or functions sought to be obtained by the present invention are the prevention of operation of a switch while a train is standing over or near a switch; allowing the switch operating mechanism or switch machine to complete a cycle of operation started prior to the entrance of a train into the controlling detector track circuit, in spite of the fact that the train has entered this track circuit; and preventing the operator from stopping an operation of the switch machine or reversing the switch after the track circuit has become occupied.

More specifically, the present invention contemplates, among other features, the provision of an electric lock controlling the usual lever of the interlocking system, con-

trolling this lock from the track circuit, and providing in addition means for assuring electric locking of a lever, irrespective of clearances demanded by practical requirements, in either of its indication positions in which operating current is supplied to a switch machine. In other words, the invention contemplates the lever lock effective in indicating positions and having associated therewith a means assuring that the lever shall be under the control of the electric lock whenever operating current can be supplied to the switch machine.

Various other characteristic features of the invention, its application to practical working conditions, and advantages will be pointed out hereinafter.

In the drawings, Figure 1 illustrates in a simplified and diagrammatic manner the principal operating parts and circuits of a well-known type of all-electric interlocking systems, together with the organization of parts and circuits embodying the invention;

Fig. 2 is an enlarged fragmentary view of the lever and the electric lock therefor showing more particularly the relative positions of the lock dog and the lever contacts;

Fig. 3 is a side elevation of one specific form of indication selector preferably employed in accordance with this invention; and

Fig. 4 is a vertical transverse section through the selector of Fig. 3, said section being taken on the line 4-4 in Fig. 3 and looking in the direction indicated by the arrows.

Referring first to Fig. 1, there is shown in a simplified and conventional manner the organization of the system embodying the invention. There is a stretch of track C with a switch D leading from the track C to a siding, turnout or crossover, it being understood that this track organization is merely a typical instance of a track layout to which the invention is applicable. The points of the switch D are connected together in the usual manner, and are operated by a switch machine or power switch-and-lock movement. In the particular arrangement selected to explain the nature of this invention, this switch machine SM is presumed to be of the type disclosed, for example, in the patent to W. K. Howe, No. 1,288,595 dated December 14, 1918, although it should be

understood that the invention is not essentially restricted to this particular type of switch machine.

The track rails 1 and 2 of the track S and 5 switch lead-out D are divided by insulated joints 3 and bonded in any one of the approved ways to provide a detector track circuit, having a track battery or other source of energy 4 and a track relay T with the 10 usual contact finger or armature 5. Since the detail construction of the switch machine SM is pointed out in the prior patent above mentioned, it will suffice to consider only those parts directly involved in making a 15 clear explanation of the present invention. These parts, shown enclosed within the dotted rectangle 7, comprise the operating motor, shown conventionally and having an armature 8 and a field 9; a circuit controller or 20 pole-changer O for governing the operating and indication circuits; pole-changer coils E for at times electrically operating the circuit controller O; and a circuit controller P for 25 governing the circuits for these pole-changer coils. The specific structure and preferred arrangement of these various parts is shown and described in detail in said prior patent; and for the present purposes, the primary 30 functions and elemental structure of these parts will be described.

The operating circuit controller O comprises an insulated contact block 10, to which are fastened conducting bars or strips 11 and 12, arranged to bridge pairs of contact 35 springs 13, 14, 15 and 16 in the different extreme positions in said contact block. As shown and described in said prior patent, the contact block 10 is operated from one extreme position, such as shown in Fig. 1, to 40 the other opposite extreme position by the final locking movement of the locking plunger of the switch machine; or, in other words, the contact block 10 is mechanically shifted from one extreme position to the 45 other upon completion of the cycle of operation of the switch machine. In addition to the mechanical operation of the contact block 10, this block may be shifted to either of its extreme positions by energization of the corresponding pair of pole-changer coils E, provided the switch machine is at an intermediate point in its cycle of operation.

The circuit controller P comprises a similar block of insulating material 17, shiftable 55 back and forth, which carries two conducting bars 18 and 19 adapted to bridge and electrically connect pairs of contact springs 20 and 21, respectively. The contact block 17 is mechanically operated from an extreme 60 position, such as shown in Fig. 1, to a middle position wherein both pairs of contact springs 20 and 21 are bridged, upon the initial unlocking movement of the switch machine, and is then shifted to the other extreme 65 position, to bridge only one pair of

said contact springs, during the final locking movement.

The principal parts of the interlocking system, located at the tower and of interest in connection with this invention, are shown in the lefthand part of Fig. 1 within a dotted rectangle 22. There is a lever L, so-called, which is essentially a flat bar 23 slideable back and forth in any suitable way. The supporting frame for the bar 23 and the other similar bars making up the machine, comprises a lever guide 24 supporting the indication mechanism 25, which being of well-known construction, need not be described in detail. It may be explained that this indication mechanism essentially consists of a latch and dog which arrest movement of the lever, or rather the bar 23, in the indication positions thereof, until the indication magnet I is energized and its armature 26 raised to trip off or release said indication mechanism.

In the bar 23 of the lever L is a cam slot 27 which drives a roller on the upper hand of the tappet bar 28, this tappet bar being connected to the usual mechanical interlocking between the particular lever illustrated and others of the complete machine in the manner and for the purpose well recognized by those familiar with this art. The bar 23 of the lever L is fastened to a handle 29 for facilitating reciprocation of said bar; and pivotally connected to this handle in the position illustrated is an angle shaped latch lever 30, the free end of which is notched and engages a fixed lug 31 so as to hold the lever against accidental displacement.

Fastened to the lever guide 24 above the bar 23 is an electric lock EL, with its latch contacts. This electric lock EL comprises a main supporting frame or casting 32, which is formed to receive a coil 33 and a core 34, making up an iron-clad solenoid, commonly termed the lock magnet. Fastened to the lower end of the core 34 is a lock dog 35 (see also Fig. 2). This lock dog 35 extends cross-wise above the lever and is guided at its ends in the lever guide 24, so that while said dog may move up and down, it can not be moved by the lever. Fixed by screws or otherwise in a recess in the upper edge of the bar 23 is a stop 36, formed with shoulders as shown to engage the lock dog 35 in the indication positions of the lever. Also fastened to the bar 23 above the stop 36 is a force-down cam 37, which is shaped or cut away as shown and engages the upper edge of the lock dog 35 and forces it down to the locking position, as more fully explained hereinafter.

The latch contact associated with the lock magnet 33 comprises an angle shaped contact finger 38 pivotally supported from an insulated block and spring pressed to the position shown in Fig. 1. The stationary insulated contact 39 is supported to be con-

tacted by the finger 38 and close a break in the energizing circuit for the lock magnet 33, whenever contact 38 is rocked. The contact 38 is shifted by a button 40 of insulating material when the latch 30 is pressed to release the lever.

The lever L is used for making and breaking certain circuits in their different positions. In the conventional arrangement shown, a rod 41 is connected to the end of the bar 23 of the lever and carries or operates insulated contact blocks 42, 43 and 44, moving these contact blocks into and out of engagement with pairs of contact springs 45 to 50, inclusive.

It may be explained here that the lever L has four significant positions, two extreme positions and two intermediate positions. In the extreme positions, commonly known as full normal and full reverse, the roller on the tappet bar 28 is at the extreme ends of the cam slot 27 with said tappet bar in its uppermost or lowermost position and the conflicting levers locked or unlocked by the mechanical locking as the case may be. In the two intermediate positions, commonly known as the normal and reverse indication positions, the roller on the tappet bar 28 is in the intermediate portion of the cam slot 27, and the indication mechanism 25 is acting to prevent further movement of the lever to the corresponding extreme position until said indication mechanism is released. The pairs of contact springs 45 to 48 are of such a length as to be engaged and electrically connected by the contact blocks 42 and 43 in the corresponding indication and extreme positions; whereas the pairs of contact springs 49 and 50 are shorter and are not connected by the block 44 until after the corresponding pairs of fingers 45 and 47 or 46 and 48 have been electrically connected by their cooperating blocks 42 and 43, the purpose of this particular arrangement being more conveniently explained hereinafter in connection with the operation.

The type of all-electric interlocking system includes, in addition to the lever L, indication magnet I and electric lock EL, a safety magnet S, a cross protection relay CP and an indication selector IS. The safety magnet S and cross protection relay CP are of the usual construction, perform their well-known functions, and need not be further discussed. The indication selector IS, however, is of a particular construction and performs a function peculiar and significant to this invention, so that it requires further consideration. One specific form of a suitable construction of the indication selector IS is shown in detail in Figs. 3 and 4.

Referring to Figs. 3 and 4, the indication selector IS comprises a rectangular open framework 52 of magnetic iron, to the end of which are fastened coils 53 and 54. Be-

tween these coils is an armature 55 which is pivotally supported near its upper end by a shaft 56, which is journaled in upstanding ears or lugs 52^a integral with the framework 52, said shaft 56 being held in the armature 55 by a small transverse pin 57. At the lower end of the armature 55 is a spring holding or over-center throwing device, which, as shown, comprises a pair of plungers 58 sliding in holes in a rocking member 59 pivotally supported on the base member of the frame 52. The plungers 58 have enlarged heads pivotally supported upon a pin 60 in the lower end of the armature 55; and compression springs 61 between the rocking member 59 and the heads of said plungers act to force and hold the armature 55 in its extreme positions. It will be readily understood that this spring device keeps the armature 55 in its extreme positions, irrespective of the de-energization of the coils 53 and 54, and also acts to force said armature to one or the other extreme position as soon as it has been shifted slightly beyond its middle position.

The armature 55 is arranged to open and close certain contacts as it is rocked back and forth. In the construction shown, two contact fingers 62 and 63 are clamped to the bifurcated upper end of the armature 55 by a plate 64 and screws 65, these fingers 62 and 63 being insulated from the armature and from each other by interposed pieces of fiber or insulating material. To the fingers 62 and 63 are riveted side contact arms 66 and 67, respectively, which rub against the edge of stationary springs 68 and 69. To the end of the frame 52 are fastened terminal blocks 70 and 70¹ of suitable insulating material, one of which, 70, supports the springs 68—69 and binding posts for the connecting wires; and fastened to both of these contact blocks 70 and 70¹ are contact pieces 71, arranged to be engaged by the ends of the fingers 62 and 63 when the armature 55 is shifted to a corresponding extreme position.

It is explained here that one important characteristic of the indication selector IS, particularly of interest with this invention, is that the coils 53 and 54 are wound relatively high resistance, such as 250 ohms, so that with one of these coils connected in series with the operating motor of the switch machine, there is not sufficient current flow for the motor to operate the switch machine.

In addition to the parts just described, the apparatus at the tower includes a suitable relay R controlled by the track relay T. The relay R is essentially a repeating relay for the detector track circuit, and may be the indicating or control relay commonly located in the tower in connection with approach locking, controlling the lights of track diagrams, etc. In the conventional circuit arrangement shown, the relay R is ener-

gized from a battery 6 by a circuit including the front contact and contact finger 5 of the track relay T, this circuit being readily traced on the drawings, so that if the detector track circuit is not occupied, the relay R is energized, but if occupied, said relay is deenergized. The relay R is shown as provided with two contact fingers or armatures 72 and 73. The contact finger or armature 72 controls the energization of the coils 53 and 54 of the indication selector in a manner more conveniently explained hereinafter in the description of the operation; and the armature 73 and its front contact determines the energization of the lock magnet 33, the circuit therefor being readily traced on the drawings as including said front contact of the relay R, a battery or suitable source 74 (which in practice is the main battery) and the latch contacts 38-39.

Operation.

The operation of the specific embodiment of this invention illustrated will be taken up in steps for the different conditions encountered in practice. A discussion of the complete operation would involve description of the interlocking system itself and the operation of its parts, but this will not be here explained in detail, reference being made to the prior patent above mentioned for further discussion of detail features or operation of the switch machine and other parts of the interlocking system.

35 *Normal operation—Detector track circuit not occupied.*—Assuming that the parts and circuits of the system are in the normal condition shown in Fig. 1, and suppose that the operator desires to throw the switch D to the other extreme or reverse position, and that the track circuit is not occupied. The operator presses the latch releasing lever 30, thereby closing the latch contacts 38-39, whercupon the lock magnet 33 is energized, since the detector track circuit is assumed to be unoccupied and the relay R is energized.

40 The energization of the lock magnet 33 raises the lock dog 35 out of engagement with the shoulders of stop 36, so that the lever is free to be moved to the opposite intermediate or reverse indication position, further movement of the lever beyond this indication position being prevented by the indication mechanism. In this reverse indication position, assuming that the operator moves the lever (pulls it out to the left as shown) as far as the indication mechanism will permit, all three pairs of contact springs 45, 47 and 49 are bridged by their respective blocks 42, 43 and 44. There is then established a circuit through the coil 54 of the indication selector as follows:—commencing at the main battery B, wire 75, safety magnet S, wires 76 and 77, finger 72 and front contact of relay R, wires 78 and 79, coil 54

of the indication selector IS, wire 80, springs 49 and block 44, wire 81, springs 47 and block 43, wires 82 and 83, springs 14 and contact strip 12, wire 84, armature 8 of the motor, wire 85, springs 13 and strip 11, wires 86 and 87, field 9 of the motor, wire 88 through the contacts 89 of the cross protection relay CR, and wire 90 back to the battery B.

45 On account of the resistance of the coil 54 of the indication selector IS which is included in this circuit, the current flowing through the armature 8 and field 9 of the switch machine motor is not sufficient to cause operation of the switch machine; but this current, however, causes the armature 55 of the indication selector to be attracted and shifted to the other extreme position, 50 rocking the contact fingers 62 and 63 from the position shown in Fig. 1 to the opposite position indicated by dotted lines, thereby establishing a shunt around the coil 54 as follows:—commencing at wire 76, wire 91, finger 63, wire 92 to the springs 47. The current now flowing through the operating motor of the switch machine is at the full strength and causes the switch machine to operate in the regular manner, unlocking switch points, throwing them to the reverse 55 position, and locking them up again. At the completion of this cycle of unlocking, shifting, and locking, the contact block 10 of the operating circuit controller O is shifted from the position shown in Fig. 1 to the opposite extreme position, breaking at the 60 springs 13 and 14 the operating circuit heretofore traced, and establishing through the pairs of springs 15 and 16 the reverse indication circuit, which includes the armature 8 and the field 9 of the motor, with their connections reversed, the indication magnet I and the contact finger 62 of the indication selector. This reverse indication circuit is conveniently traced starting at the armature 8 as follows:—commencing at the upper 65 brush of the armature 8, wire 93, springs 15 and strip 11, wire 87, field 9, wire 88, contacts 89 of the cross protection relay, wire 94, winding of the cross protection relay CP, wire 95, indication magnet I, wire 96, finger 62 of the indication selector IS (now shifted to the dotted line position), wire 97, springs 45 and block 42, wires 98 and 99, springs 16 and strip 12, and wire 100 back to the lower 70 brush of the armature 8.

75 It will be noted that this indication circuit just traced includes the armature and field of the operating motor, with their connections reversed, and the comparatively 80 low resistance of the indication magnet I and cross protection relay CP. The armature of the motor is rotating, and in accordance with well-known principles acts as a generator to produce dynamically a momentary 85 indication current which energizes the indi- 90

cation magnet I, releases the indication mechanism and frees the lever, so that the operator may complete the movement of the lever to the full reverse position and release 5 the mechanical interlocking associated with conflicting levers.

The operation involved in returning the switch D from the reverse position back from the normal position shown is substantially the same as described, and analogous 10 circuits which can be readily traced on the drawings without further explanation, are involved in this operation.

Normal operation—Detector track circuit occupied.—In the foregoing description of the operation, it was assumed that the relay R is energized, this being the condition existing when there is no train upon the track circuit. Assume, however, that there is a train or car 20 standing on some part of the detector track circuit at the time the operator attempts to shift the lever L. Under these conditions, it is evident that it should not be possible to apply power to the switch machine and 25 either unlock or move the switch points. According to the particular arrangement illustrated, the application of power to the switch machine is prevented for two reasons. In the first place, since the detector track 30 circuit is occupied and the relay R deenergized, the lock magnet 33 can not be energized and the operator can not move the lever beyond the normal indication position. In the second place, even though the 35 lever could be placed in the reverse indication position, the circuit for energizing the coil 54 of the indication selector would be interrupted at the finger 72 of the relay R, so that no current could be supplied to the 40 switch machine.

Switch started—Train enters detector track circuit.—Occasionally in practice conditions may be organized such that, just after the operator has shifted his lever, say 45 to the reverse indication position, and just after the switch machine has commenced its cycle of operation, a train enters the detector track circuit. After some consideration, it will be readily appreciated that, from the 50 standpoint of safety, it would be preferable to allow the switch machine to complete the cycle of operation it had started rather than stop such operation and leave the switch points partly open or unlocked, in spite of 55 the fact that ordinarily a train on the detector track circuit should prevent operation of the switch. This requisite is taken care of in the present invention by reason of the fact that, after the indication selector IS has 60 once responded, the operating circuit is set up and remains intact until broken at the switch machine, even though the relay R may be deenergized. Consequently, after 65 the lever has been shifted, the indication selector has responded, and the cycle of

operation of the switch machine has started, then the entrance of a train into the track circuit is not effectual to arrest or prevent operation of the switch.

In addition to allowing the switch machine to complete the cycle of operation once started prior to the entrance of a train into the detector track circuit, it is also desirable and important to prevent the operator from accidentally or carelessly himself stopping 70 this operation and leave the switch partly opened or unlocked; more particularly prevent the operator from reversing or attempting to reverse the switch. Putting it another way, if it should happen that a 80 train gets into the detector track circuit while the switch machine is operating, it is important, not only to allow the switch machine to complete the existing cycle of operation, but also prevent the operator from 85 stopping that cycle and particularly from reversing switch points. The reason for this may be best appreciated by imagining a train approaching and about to pass over the switch, and visualizing the operator at the 90 distant tower, frequently out of view of the train entirely, shifting the lever back, perhaps because he has just realized that no attempt should have been made to throw the switch; or, as has actually happened, the 95 operator, in ignorance of the presence of the train or perhaps excited shifts the lever first one way and then the other, and "splits" the train, part going one way and part the other. 100

According to the present invention, it is not possible for the operator to stop a cycle of operation once started, after the detector track circuit has become occupied, nor is it possible for him to reverse the switch. Since 105 the detector track circuit is occupied, the relay R is deenergized, and the lock magnet 33 is deenergized. This holds the lever in the corresponding indication position. The operator can not pull the lever back from 110 that indication position far enough to cut off operating current, for the reasons about to be explained, much less shift the lever to the other indication or operating position and cause reversal of the switch. The 115 safeguard against reversal is also obtained by virtue of the control of the indication selector by the relay R, since this indication selector can not be changed and current applied to reverse the switch, while the track 120 circuit is occupied.

The particular feature of this invention of prominent importance, resides in the particular provisions made to assure locking of the lever in the indication position. Heretofore it has been attempted to provide a lever lock which will hold the lever in the indication positions as well as in the usual full normal or full reverse positions. Speaking of the indication position as the point 125

where electrical connection is first made to set up the operating circuits, that is, the point where the contact blocks 42 and 43 first engage the contact springs 45 and 47, for example, it has been found impractical, on account of the problems of mechanical clearance, to provide an electric lock which will be effective in the indication positions of the lever. In the first place, it will be readily recognized that there must be some clearance between the edge of the lock dog 35 and the shoulder of the stop 36 with which it engages (see Fig. 2). Likewise, for mechanical reasons, there is necessarily some slight variation in the precise point in the movement of the lever where the contact blocks first touch their contact springs. Now, if the locking shoulder of the stop 36 and the edge of the lock dog 35 are selected so that, before engagement of the contact blocks with their springs, the lever must be moved far enough to give sufficient mechanical clearance to allow the dog 35 to drop behind the shoulder on the stop 36, then the operator would be able to defeat the purposes of the invention and cut off current from the switch machine in spite of the lever lock by forcing the lever as far as the dog 35 would permit, whereupon the contacts would be broken and the circuit interrupted, because the parts have been purposely proportioned to leave clearance between said dog and its locking shoulder before the contacts were closed. On the other hand, if it is attempted to make the parts accurately, such that the dog 35 will drop behind the shoulder on the stop 36 at the same point in the movement of the lever where the contact blocks engage their pairs of springs, then on account of mechanical clearances required and slight variations occurring in practical operation, the operator would be able to defeat the purpose desired by moving the lever up to the point where contact is made but the lock dog 35 has not cleared the shoulder and is not able to drop. This problem of clearance, nicety of adjustment and variations of wear and usage have all been obviated by the adoption of the expedients characterizing this invention. Before it is possible to supply effective operating current to the switch machine, the indication selector IS must respond; and before this can happen, the contact block 44 must be in engagement with the short springs 49 or 50. If the lever has been moved far enough, say to the position illustrated in Fig. 2, for the contact block 44 to just touch the short springs 49, then the blocks 42 and 43 will have been wiped a considerable distance over the pairs of springs 45 and 47. Considerable clearance, therefore, may be provided between the lock dog 35 and its shoulder, as indicated in Fig. 2, with assurance that, if the operator shifts the lever back as far as the lock dog will permit, the electrical connection through the fingers 45 and 47 will still be maintained. The latitude in the clearances afforded by the adoption of the short springs 49 and 50 and their interconnection with the indication selector IS also facilitates the application of the force-down principle, and makes it possible to provide a force-down guide cam 47 which will perform the proper function.

In view of the special provisions for assuring the engagement of the electrical lock in the indication position of the lever, the system of this invention positively prevents the operator from cutting off current to the switch machine and arresting its cycle of operation while a track circuit is occupied, because the electric lock holds the lever at the existing end of its movement so long as the track circuit is occupied.

Simultaneous movement of the lever and entrance of train.—The control of the indication selector IS by the track circuit through the agency of the relay R and its front contacts 72 is particularly effective for the rather rare condition where the train enters the track circuit substantially simultaneously with the movement of the lever. Imagine that the operator, with the lever in the normal position shown, releases the electric lock and starts to move the lever to the reverse indication position, and assume that just after the lock has been released and such movement of the lever is started, the track circuit becomes occupied. Under this particular set of conditions, it may be considered desirable to prevent operation of the switch machine and leave the switch undisturbed in its existing position. So far as the electric lock EL is concerned, however, an operation of the switch machine will occur under the particular conditions recited, inasmuch as the lock has been released before the track circuit becomes occupied. The indication selector IS and its control by the track circuit, however, takes care of this particular contingency and prevents the application of defective operating current to the switch machine, since the relay R will be deenergized and its front contacts 72 open at the time the lever reaches its reverse indication position.

Another rare contingency exhibits advantages and the protection afforded by the indication selector and its control by the track circuit, as compared with the protection afforded by the electric lock alone. To illustrate, it may happen for some peculiar reason that the operator has the lever in an intermediate or middle position between the indication points at the particular instant the train enters the track circuit. Although the electric lock EL is of course deenergized on account of the occupancy of the track

circuit; this lock is ineffective because the lever is not in either indication position where it can be locked. Consequently, so far as the electric lock alone is concerned, the operator could move the lever from the intermediate position assumed to the indication position opposite to the existing position of the switch, apply power to the switch machine and shift the switch in spite of the presence of the train. The track circuit control of the indication selector IS, however, prevents operation of the switch machine under these peculiar conditions, since with the relay R deenergized and its front contact 72 open, no current can be supplied to the switch machine.

Preferred arrangement.—While, for reasons above explained, it is desirable to provide track circuit control of the indication selector, in addition to and supplementary to the track circuit controlled lever lock, the conditions under which such track circuit control of the indication selector is capable of affording protection not provided with the lever lock alone are rather rare and exceptional, so that for ordinary operating conditions it is frequently found sufficient to provide the lever lock EL and its associated control parts, omitting the control of the indication selector IS by the relay R. With this arrangement, which may be said to be the preferred form of the invention on account of its simplicity, the front contact 72 of the relay R is omitted together with wiring connections 77 and 78, and two coils 53 and 54 of the indication selector are directly connected on one side to the battery B, as for example, by connecting the wire 91 to the point where wires 78 and 79 join. With this adaptation of the invention, the track circuit has no direct control over the supply of power to the switch machine and serves merely to determine the energization of the electric lock EL. The indication selector IS, its shunting contacts 63, and the short contact springs 49 and 50 are employed in connection with the lever lock, for reasons hereinbefore explained, so as to assure locking of the lever in its indication positions, with due allowance for mechanical clearances and performing locking in such a fashion as to prevent opening of the regular lever contacts by manipulation of the lever within the limits of movement allowed by the clearance of the electric lock.

It may be said that the principal characteristic feature of this invention resides in the organizing of the high resistance indication selector, its shunting contacts, and the short contact springs 49 and 50, in conjunction with a lever lock of the force-down solenoid type shown. Putting it another way, the regular contact springs 45—48 may be considered as made somewhat longer than ordinarily so as to be engaged by their con-

tact blocks 42 and 43 for some distance at the indication positions of the lever, this distance being greater than that through which the lever may be shifted on account of the mechanical clearances of the lever lock. In this connection, it is of course to be understood that the indication mechanism 25 arresting movement of the lever in the indication position does not stop movement of the lever until the contact springs 49 or 50 are bridged by the contact block 44. In other words, if the operator pulls a lever as far as the indication mechanism 25 permits, then the contact springs 49 or 50, as the case may be, are connected by their contact block 44, and likewise the pairs of contact springs 45—47 or 46—48 are connected by their contact blocks 42 and 43 a considerable distance of wipe sufficient to assure maintenance of the operating circuit even though the lever is backed off as far as the electric lock will permit.

In the foregoing discussion of the operation, particularly where certain conditions have been assumed, complication has been avoided by omitting explanation of the effect of signal indication, route locking arrangements, time element or push button releases, and various other auxiliary devices commonly used in accordance with modern practice in connection with power interlocking systems; and it should be understood that these auxiliary devices or features of the complete system, for reasons well recognized by those skilled in the art, may modify or make exceptionally difficult the particular combinations of conditions or contingencies discussed. For example, a power interlocking system of a modern type, through the agency of signal indications, sometimes automatic train control or stops, route interlocking, and other auxiliary arrangements of devices, makes it necessary for certain peculiar combinations of circumstances to occur before a train may enter a track circuit while the switch machine is operated. Likewise, the skill and care of the operator ordinarily used has been disregarded to a large extent in the foregoing discussion of the operation and advantages of this invention.

While one specific and particular construction and organization of devices and circuits, and one specially designed and adapted for use in connection with a certain type of all-electric interlocking system has been selected and explained to give a disclosure of this invention, it will be evident to those skilled in the art that various and obvious modifications and adaptations of this specific disclosure may be made in practice without altering the nature and essential characteristics of the invention; and we desire to have it understood that this specific system disclosed is merely illustrative.

of the invention, and that various other forms and means may be provided to constitute the invention.

What we claim is:—

5. 1. In an electric interlocking system, the combination with a track switch, a detector track circuit, a switch machine for operating the switch, a lever for controlling the operation of the switch machine from a distant point, an electric lock for the lever controlled by said track circuit and operable to prevent movement thereof beyond an indication position toward the other extreme position, the co-acting parts of said lock having a mechanical clearance permitting slight movement of the lever at the indication position, means adaptable to prevent operation of the switch machine, and means for rendering said preventing means ineffective for each position of the lever only after the lever has been moved far enough to allow engagement of the coacting parts of the lever lock.

2. In an electric interlocking system, the combination with a track switch, a detector track circuit, a switch machine for operating the switch, a lever for controlling the operation of the switch machine from a distant point, an electric lock for the lever controlled by said track circuit and comprising, a lock dog and a stop secured to the lever and provided with shoulders engageable by said lock dog, and automatic means preventing operation of the switch machine by movement of the lever to an indication position until the lever has been moved some distance beyond the point where said lock dog may pass back of a shoulder on said stop.

40 3. In an electric interlocking system, the combination with a track switch, a detector track circuit, a switch machine for operating the switch, a lever for controlling the operation of the switch machine from a distant point, an electric lock controlled by said track circuit for holding said lever in its indication positions, contacts operated by the lever for controlling the switch machine and closed for some distance of movement of the lever at the indication positions, and automatic means preventing operation of the switch machine until said contacts have been closed for a range of movement of the lever greater than permitted by the electric lock.

45 4. In an electric interlocking system of the type described, a lever, an electric lock for holding said lever in its indication positions, contacts operated by the lever and closed for some distance of movement thereof at their indication positions, other contacts operated by the lever and closed only after the first mentioned contacts have been closed for said distance of movement, and 55 means controlled by said other contacts for

governing the supply of current through the first mentioned contacts.

5. An electric interlocking system of the type described, a switch machine, control circuit for said switch machine, a lever and contacts operated thereby for governing said control circuits, an electric lock for holding said lever in its indication position but permitting slight movement thereof due to mechanical clearances between the cooperating parts of said lock, said contacts governing said control circuits being closed throughout said range of movement of the lever at its indication positions, and automatic means preventing operation of the switch machine until the lever has been moved substantially through said range of movement at an indication position, whereby the switch machine can not be operated until the lever has been moved far enough to assure engagement of the electric lock and closure of its controlling contacts in spite of the lost motion afforded the mechanical clearances of the co-operating parts of the electric lock.

6. In an electric locking arrangement for levers of the power interlocking systems, the combination with a lever, of an electric lock holding said lever in its indication positions but permitting slight movement thereof, operating contacts connected to the lever and closed throughout said range of movement, and other contacts closed only after said lever has been moved to the extreme of said range of movement.

7. In an electric interlocking system, the combination with a lever and an electric lock therefor effective at the indication positions of the lever, said electric lock on account of mechanical clearances affording some lost motion of the lever, of long and short contact springs, and contact blocks connected to said lever and engaging said contact springs.

8. In an electric interlocking system, the combination with a switch machine and a lever for controlling the operation thereof, of an electric lock for said lever effective in the indication positions of the lever and permitting slight movement of the lever at said indication positions, and automatic means for preventing the supply of effective operating current to the switch machine until said lever shall have been moved toward its extreme position throughout the range of movement afforded by said electric lock, whereby operation of the switch machine is prevented until the lever has been moved far enough to assure locking thereof by said electric lock.

9. In an interlocking system of the type described, a switch, a switch machine for operating the switch, a detector track circuit associated with said switch, a lever at a distant point for controlling the operation of the switch machine, an indication selector associated with the lever and having high

resistance coils alternately included in the operating circuits for the switch machine, said coils limiting the flow of current to an amount insufficient to permit operation of the switch by said switch machine, an electric lock for the lever controlled by said track circuit and operable near an extreme position thereof to prevent movement to the other extreme position, and means for establishing a shunt of low resistance for the coils of said indication selector only after said lever has been moved to its extreme position beyond the point where said electric lock prevents return of the lever to the other extreme position.

10. In an electric interlocking system, the combination with a lever, a track circuit controlled electric lock therefor, said lock being effective in the indication positions of said lever, an indication selector having high resistance coils, contacts operated by said selector for establishing a shunt of low resistance around the corresponding coil, and contacts operated by the lever for establishing a circuit through said coils of the indication selector alternately, said contacts being closed only after the lever has been moved beyond the point where said electric lock is effective.

11. An electric interlocking system of the type described comprising, a switch, a switch machine operating the switch, a detector track circuit associated with said switch, a lever controlling the operation of the switch machine, an electric lock for the lever effective in the indication positions, an indication selector having high resistance coils, and means for establishing a shunt of low resistance around each coil of the indication selector in turn as the lever is moved to its indication positions, said means being effective only after the lever has been moved beyond the point where said electric lock is effective and provided said track circuit is not then occupied.

12. In an electric interlocking system of the type described, a movable lever, indication mechanism for said lever limiting the movement thereof to its extreme positions at a predetermined indication point, an electric lock operable to lock said lever near said indication point but permitting slight movement of the lever from said indication point toward the other extreme position, contacts operated by the lever and closed throughout the range of movement thereof between said indication point and the point where said lock prevents movement of the lever, and other contacts operated by the lever and closed only after said

lever has been moved fully to said indication point.

13. In an electric interlocking system of the type described, the organization of parts operating substantially as described and comprising, a lever, an electric lock therefor effective in the indication positions, an indication selector having high resistance coils, and pairs of long and short contact springs, said long spring including the control circuits governed by the lever, and the short springs the energizing circuits for said coils of the indication selector.

14. In an electric interlocking system, the combination with a movable control lever, of an electric lock effective to limit movement of said lever in one direction in a predetermined position of the lever, a power-operated device controlled by the movement of said lever, and means requiring movement of the lever to a point where said electric lock will become effective irrespective of mechanical clearances between its co-operating parts, before said device will be controlled by the lever.

15. In an electric interlocking system, the combination with a movable lever, contacts closed by movement of said lever to a predetermined position, a power-operated device and a control circuit therefor including said contacts, an electric lock for said lever having a movable lock dog, said lever being formed with a shoulder with which the lock dog may engage and prevent movement of the lever in one direction, means movable with the lever and engaging said lock dog to force it into locking cooperation with said shoulder, and automatic means preventing operation of said power-operated device by closure of said contacts unless the lever is moved far enough to force the lock dog into position to engage said shoulder.

16. In an electric interlocking system, the combination with a movable lever, contacts closed during a limited range of movement of said lever near one extreme position, locking means effective to hold mechanically said lever against movement from said position far enough to open said contacts, a power-operated device having a control circuit governed by said contacts, and automatic means preventing operation of said device irrespective of the closure of said contacts unless the lever is moved far enough to permit said locking means to be effective.

In testimony whereof we hereby affix our signatures.

PAUL E. CARTER.
ROY CONNELL.
